UNITED STATES PATENT OFFICE.

MEREDITH G. STANLEY, OF CINCINNATI, OHIO.

STAMP.

1,206,735.

Specification of Letters Patent Patented Nov. 28, 1916.

Application filed October 19, 1912. Serial No. 726,740.

To all whom it may concern:

Be it known that I, MEREDITH G. STANLEY, citizen of the United States, residing at Cincinnati, in the county of Hamilton and State of Ohio, have invented certain new and useful Improvements in Stamps, of which the following is a specification, reference being had therein to the accompanying drawing.

10 This invention relates to stamps and has for its object the production of a simple and efficient stamp which will automatically feed the paper to the proper position after each operation in order to allow the 15 stamp to record or register each item stamped when using the device.

Another object of this invention is the production of a simple and efficient feeding mechanism for the ribbon and carbon sheets 20 which will automatically cause the carbon and ribbon to come to the desired position for allowing each item stamped to be successively recorded.

With these and other objects in view, this 25 invention consists in certain novel constructions, combinations and arrangements of parts, as will be hereinafter fully described and claimed.

This invention is illustrated in the accompanying drawings, wherein:

Figure 1 is a central longitudinal section of the stamp. Fig. 2 is a section taken on line 2—2 of Fig. 1. Fig. 3 is a section taken on line 3—3 of Fig. 2. Fig. 4 is a section taken on line 4—4 of Fig. 1. Fig. 5 is a section taken on line 5—5 of Fig. 2. Fig. 6 is a detail perspective of the stamp showing the outer side of the casing. Fig. 7 is a detail perspective of the bottom plate of the stamp casing. Fig. 8 is a detail perspective of the closure plate for the stamp casing. Fig. 9 is a plan view of one of the indicating bars. Fig. 10 is a side elevation of one of the ribbon and paper supporting shafts. Fig. 11 is a fragmentary view of one of the side walls of the inner casing showing one of the paper roll supporting shafts in end elevation. Fig. 12 is a section taken on line 12—12 of Fig. 9. Fig. 13 is a plan view of the spring plate for holding the rack bars in a locked position. Fig. 14 is a transverse sectional view through the carbon sheet containing roller. Fig. 15 is a section taken similar to Fig. 1 showing the modified structure. Fig. 16 is a section taken similar to Fig. 3 showing the modified structure. Fig. 17 is a central horizontal section through the casing showing the modified structure. Fig. 18 is a section taken on line 18—18 of Fig. 16. Fig. 19 is a detail perspective of the forward end of the releasing rod.

By referring to the drawings by numerals, it will be seen that 1 designates the outer or top casing which is provided with a plurality of parallel slots 2. Within these slots 2 work the operating knobs 3 which knobs engage at their lower ends the indicating bars 4. These indicating bars 4 are provided with an indicating plate 5 containing a series of figures and symbols adapted to correspond with the symbols and letters or figures contained upon the stamping disks 6. These indicating plates 5 are placed in the substantially U-shaped channel 7 formed in the outer faces of the indicating bars 4. These indicating bars 4 are provided with a plurality of disk operating teeth 8 which teeth are adapted to engage the operating teeth 9 formed upon the stamping disks 6. These teeth 8 straddle the stamping teeth 9 formed upon the periphery of the disks 6 and these teeth are adapted to be engaged upon either side by the teeth 8 of the indicating bars 4. There are preferably twelve of these teeth 9 and the teeth 8 are so formed upon the lower face of the indicator bars 4 as to register with the teeth 9, and notches 10 are formed between the teeth 9 so as to prevent injury to the type. These disks 6 are supported upon the central supporting shaft 11 which has its respective ends journaled in the side walls 13 of the inner casing. These disks are so formed as to indicate a key number to the left of the row of figures followed by the month of the year which is in turn followed by a pair of disks for indicating the days of the month which last mentioned disks are followed by the years, for instance 1912. A plurality of numbered disks are placed to the right of the disk containing the years for the purpose of stamping the desired numbers which may be desired to be used in connection with the present stamp. A washer 10' is carried by the shaft 11, to one side of the number disks.

By means of the bar 4 and the disks 6 as described, it will be seen that these disks may be rotated to the desired point by shifting the bars 4 within the slots 2 formed in the outer casing 1. A transversely extend-

ing aperture 12 is formed adjacent the forward ends of the slots 2 through which may be viewed the numbers of the indicating bars 4. The side walls 13 of the inner casing are held together by means of tie rods 14, and one of the walls 13 is provided with a plurality of slots 14' which extend from the under surface of the walls for admitting the paper and ribbon supporting shafts 15.

10 One end of each of the shafts 15 is provided with an enlarged head 16 having adjacent thereto reduced necks 17 which necks 17 are adapted to be engaged by the curved fingers 18 of the shaft locking bar 19. A plurality of these fingers 18 are formed upon the under surface of the bar 19 so as to grip all the ribbon and paper containing rollers. This bar 19 is supported upon the outer face of one of the walls 13 of the inner casing as illustrated clearly in Fig. 5 by means of the supporting pins 20, which pins are placed through the elongated slots 21 formed in the respective ends of the locking bar 19. These slots 21 allow the rod or bar 19 to be shifted longitudinally of the inner casing. A spring latch 22 is carried by the outer face of the inner casing and engages the end of the bar 19, thereby holding the bar 19 against accidental movement.

20 This spring latch member 22 may, however, be removed from engagement with the bar 19 so as to allow the bar 19 to have longitudinal movement relative to the inner casing for removing the shafts 15 when it is desired to remove the paper from the roll and remove the ribbon which is used in connection with the stamping device. Of course, it should be understood that the roller which contains the stamping ribbon

25 may be provided with a reversing mechanism for causing the same to automatically return after the ribbon has once been wound upon the opposite roll. The opposite end of each shaft 15 is reduced so as to constitute a flattened portion 24 and over this flattened portion 24 fits the ratchet wheel 25. The projecting lug 26 formed upon the outer end of each shaft 15 carries a ratchet wheel 25. By means of this construction just described, it will be seen that the ratchet wheels 25 will be firmly locked in engagement with the shafts 15. These ratchet wheels 25 are interposed between one of the walls 13 of the inner casing and one of the walls 28 of the outer casing. A pawl 29 is carried by one of the walls 13 of the inner casing and engages the primary ratchet 30 for holding the same against rotation in one direction. The auxiliary ratchets 31 are engaged upon the under surfaces by means of the pawls 32 which pawls are held in engagement with the ratchet wheels 31 by means of the springs 33. A flat spring 34 engages one of the auxiliary ratchets 31 for retarding the rotation there-

30 of. These pawls 32 are supported by the rearwardly extending arm 35 of the operating frame 36. This operating frame 36 comprises an angular structure having its oppositely extending arms 35 and 37 connected by means of a vertically extending portion 38. A coil spring 39 is connected to the vertically extending portion 38 near its upper end and has its opposite end secured to one of the side walls of the inner casing so as to resist the forward movement of the frame or keep a tension thereon. The forwardly extending arm 37 of the operating frame 36 is provided with a notch or cut-away portion 40 upon its under face in which works a lug 41 carried by one of the side walls 13 of the inner casing. This lug 41 engages the shoulder 42 of the arm 37 and limits the rearward movement of the frame 36.

35 A link member 43 is connected to the outer end of the arm 37 and in turn is connected to a bell-crank lever 44 which bell-crank lever is pivotally secured to one of the side walls 13 of the inner frame as indicated at 45. The bell-crank lever 44 engages the outer end of the operating lever 45 which lever is provided with a rearwardly extending foot 46 adapted to be engaged by the laterally extending pin 47 carried by the upwardly extending lugs 48 of the bottom plate 49. The operating lever 45 is provided with a slot 48'. The bottom plate 49 is also provided at its rear end with a plurality of upwardly extending ears 50 which are pivotally secured to the rear end of the outer casing 1. A notch 51 is formed in the side walls 13 of the inner casing near the rear end thereof so as to allow the bottom plate 49 and the closure plate 52 to be swung to a sufficient distance without binding upon the end of the outer casing 1 so as to facilitate access to the interior of the stamp. An aperture 53 is formed upon the bottom plate 49 near its forward end so as to allow access to be had to the lock 54 of the closure plate 52.

40 The closure plate 52 comprises an elongated body having upwardly extending ears 55 which ears are pivotally secured to the side walls 13 of the inner casing for facilitating the swinging of the closure plate to allow access to be had to the interior of the casing. An aperture 56 is formed in the closure plate 52 to allow the ribbon and carbon sheets to be acted upon for impressing the desired figures or symbols upon the sheet contained between the bottom plate 49 and the closure plate 52. The sheet is adapted to rest upon the raised padded portion 58 formed upon the inner face of the plate 49. Notches 57 are formed upon the side edges of the closure plate 52 through which notches pass the upwardly extending lugs 48 of the bottom plate 49.

The laterally extending pins 47 above described will limit the outward movement of the bottom plate 49 relative to the closure plate 52 for the reason that these pins 47 5 will engage the inner face of the closure plate 52 in view of the fact that these pins overhang the side edges thereof. As above stated, a lock 54 is carried by the forward end of the closure plate 52 and engages the 10 inner casing so as to prevent anyone from interfering with the interior of the stamp.

A pair of spring members 59 are formed upon the inner face of the bottom plate 49 so as to normally hold the bottom plate 49 15 away from the closure plate 52 thereby allowing a sheet of paper or other material to be inserted between the closure plate 52 and the bottom plate 49 in order to allow the stamping device to easily engage a sheet of 20 paper or other material adapted to be stamped. Upon the inner shafts is adapted to be wound an inking ribbon 60 which ribbon is adapted to be actuated or stamped upon the white face of the carbon carrying 25 web 61 which is rolled upon the outer rollers. The under face of the carbon carrying web 61 is adapted to make an impression through the medium of the stamping teeth 10 of the disks 6 upon a web of 30 paper placed directly thereunder. Rollers 62 are carried by the side walls 13 of the inner casing and engage the inner face of the web 61 to protect the same. One of the rollers 62 is adapted to hold the web 61 35 from rubbing upon the sharp edge of the stamping plate 63 of the inner casing.

A plate 64 is carried by the inner casing near the upper end thereof through which the outer faces of the disks 6 extend, and 40 this plate is secured to the sides of the inner casing by means of the arms 65. A plurality of springs 66 are secured to the under faces of the plate 64 to register with the indicator bars 4 and these springs are provided 45 with upwardly extending bulged portions 67 which engage the teeth 8 formed upon the lower faces of the bars 4. A locking lever 68 is pivotally secured to the outer casing and is provided with a transversely 50 extending bar 69 at its outer end for engaging the spring 67 between the teeth 8 whereby the bars 4 may be held against accidental movement after having once been set.

55 The operation of the device is as follows: The sheet of paper to be stamped is placed between the lower plate 49 and the closure plate 52 and pressure is brought to bear upon the outer casing forcing the outer casing down upon the lower plate which will, of course, cause an impression to be made upon the paper and at the same time the teeth 10 will form an impression upon the rear face of the carbon web 61, which for 60 the present purpose is white, thereby mak-

ing a permanent record of each item stamped. At the same time the lugs 47 will engage the projecting foot 46 of the operating lever 45 which will cause the frame 36 to move forward and enable the ratchet 70 pawls 32 to engage the next succeeding tooth upon the ratchet wheels 31. As soon as the pressure is relieved from the casing 1 the spring 39 will return the frame 36 to its normal position thereby causing the 75 ratchet pawls 32 to rotate the ratchet wheels 31 which will in turn unwind the ribbon 60 and the carbon 61 from their respective rollers and rewind the same upon the shafts 15 engaged by the gear wheels 31. By following out this operation it will be seen that a 80 fresh impression will be made upon the carbon web each time an item is stamped thereby making a permanent record and furnishing a clean place upon the carbon web 85 for producing a clear and distinct impression upon the sheet placed between the closure plate 52 and the bottom plate 49. The disks 6 may be adjusted as previously described for determining the desired figures 90 in order to make up the impression desired.

Fig. 13 is a top plan view of the spring plate 66 showing all of the tooth engaging portions 66' integrally connected at their rear ends to a body portion 67.

Fig. 14 shows the carbon containing roller wherein two sheets may be employed instead of one as previously described so as to enable the plain white web to be removed from the roller and be independent from the carbon web which is wound with the white web. This white web may be placed away as a record and it will be seen that there will be no carbon backing which would be likely to smear the contents of a file when the contents is placed therein.

By carefully considering Fig. 1 it will be seen that the face of the type formed upon the teeth will be protected from becoming injured in view of the fact that the sockets between the teeth formed upon the rack 4 are provided with socket portions 4' for allowing the face of type to extend therein. These sockets 4' are so formed as to prevent the outer face of type from engaging any 110 portion of the rack bar 4.

As illustrated in Figs. 15, 16, 17 and 18, I have shown an embodiment of my invention wherein the spring 39 as illustrated in Fig. 3, is eliminated. The lever arm 72 in 120 place of being pivoted as indicated in Fig. 3, is provided with a rounded outer end 70 which outer end 70 fits in a semicircular notch 71 formed in one of the ears 48. This notch 71 constitutes a fulcrum or pivot point 125 for the lever arm 72 as indicated in Figs. 15, 16, 17 and 18, and to the outer end 70 is secured an angularly extending end 73 of the pivot connecting rod 74. The outer end 73 of the rod 74 passes through a slot 75 130

formed in one of the side walls 13 of the inner casing so as to allow the outer end 70 of the lever arm 72 to be moved into and out of engagement with the notch 71 formed in one of the ears 48. This rod 74 is provided at its forward end with an oppositely extending arm 76 which is provided with an aperture 77 in which aperture fits the tongue 78 for holding the rod 74 against longitudinal movement. This tongue 78 is provided with a plurality of shoulders 79 which shoulders are adapted to hold the rod 74 in its correct locked position when the lock is set. The plunger, of course, is adapted to have sufficient movement as to allow the rod 74 to freely slide a sufficient distance to remove the end 70 of the lever arm 72 from the notch 71 when it is desired to swing the plates 49 and 52 from the outer casing 1. An operating finger 80 is also secured to the rod 74 and projects laterally of the casing 1 so as to allow the rod 74 to be moved back and forward after the lock 54 has been released.

From the foregoing description it will be seen that a very efficient device has been produced whereby the spring 39, as illustrated in Fig. 3, will be eliminated since the opening of the bottom plate 49 relative to the casing 1 will be caused by means of the spring 59 exclusively. It will also be seen that the lever arm 72 may easily be released from the ear 48 by shifting the rod 74 longitudinally of the casing 1.

It will thus be seen that I have produced a portable printing stamp in the nature of an oblong box-like structure substantially thin so as to be conveniently carried in the pocket.

A primary field of usage for devices of this character suggests itself in the work of bill collection. It is my primary purpose to use this stamp in connection with an office system wherein the statements are issued under serial number. My stamp would, therefore, preferably comprise serial figures or statement identifying indication, a date indication and an indication of the amount of the statement. The stamped statement is the receipt, a duplicate being taken and recorded in the stamp for office corroboration, whereby a check is automatically kept on the operations of the collector, besides facilitating his manual labor and obviating the necessity of any written transaction. A machine to be pocket contained must be compact, easily manipulated, efficient and accurate in operation.

It will be noted that the thickness of the unitary housing body, which coacts with the thin platen plate, is approximately equal to the diameter of the printing disk, and that the one periphery of the disk projects through the housing adjacent the platen, while the diametrically opposite disk per-

iphery lies immediately under the cover plate on the other side of the housing, the disk operating, locking and character indicating devices being substantially compacted into the tangential plane of the type disk immediately under the cover plate, so that the diameter of the printing disk is approximately the same as the lateral dimensions of the unitary housing body coacting with the platen. The spaces between the teeth of the rack bar correspond in number to the type teeth of the disk and the upper surface of the bar immediately over said spaces display the serial disk characters through the cover plate, whereby the longitudinal area of the stamp, as well as the cross sectional area are reduced to a minimum, thus primarily adapting the stamp and its organized mechanism to the portable usage indicated. This feed mechanism is spring controlled to impart step movements to the rolls, and is actuated by the relative movement of the housing body and platen plate, so that the same tension serves in its reaction to actuate the feed and to influence the normalizing of the housing body and platen plate, or hold them apart for inserting the article to be stamped.

The spring leaf coacting with the rack bar has a knobbed free end engaging upwardly between the rack teeth and coacting therewith to function both as a cam and a latch. That is, as a bar is manually shifted, the spring is depressed, and after a tooth has moved forward, the cam-like portion of the knob pressing upwardly against the edge of the tooth, definitely completes the bar movement to bring the type disk to an exact and invariable stamping position, at the same time engaging latch-like between the rack teeth to maintain the definite adjustment. It is obvious that with this disclosure in mind, the same inventive principles might be variously embodied in different specific constructions comprehended by the claims except in so far as they are expressly limited to preferred constructions and arrangement of parts. Another phase of this invention, enabling the condensation of operating mechanism into an organized pocket-stamp, comprises the character and disposition of the feeding devices. The unitary housing body, constitutes one jaw and the hinged platen plate the other jaw of the stamp. The housing body comprises an inner frame in which the printing disk and the record and inking strip rolls are rotatably mounted, the rolls being disposed upon opposite sides of the disk enabling the diameter of the disk to determine the thickness of the unitary body element of the stamp, and enabling the pigment and record strips to pass between the disk and platen, so that a single platen is utilized for the record strip and the article inserted between the

the jaws for stamping, thus compacting the working parts into a small space. This is further made possible by the disposition of the lever, pawl and ratchet roll feed mechanism on a side wall of the inner casing, enclosed by the side wall of the cover plate.

Having thus described the invention, what is claimed as new is:

1. A printing attachment for a recording stamp comprising a disk, said disk provided with a plurality of teeth formed upon its periphery, each tooth provided with a type face of less width than said teeth, a rack member provided with a plurality of teeth upon its under surface, said teeth adapted to straddle said teeth formed upon said printing disk and adapted to engage the sides of said teeth upon said printing disk for rotating the printing disk when said rack is shifted,
- 10 and said rack provided with a notched portion between each tooth for constituting a pocket for receiving the type face formed upon the outer faces of the teeth formed upon said printing disks and constituting
- 15 a protector for the face of the type formed upon said printing disks.

2. A receipt register of the class described comprising a body, a bottom plate hingedly secured to said body, printing means carried by said body, a pigment carrying ribbon carried by said body and passing under said printing means for causing an impression to be made therethrough, means for feeding said pigment, an operating lever cooperating with said feeding means and provided with a rounded forward end, said plate provided with an upwardly extending ear having a circular notch formed therein, and means engaging the forward end of said lever for holding the same in engagement with said notch.

3. A receipt register of the class described comprising a body, a bottom plate hingedly secured thereto, a closure plate secured to said body, said bottom plate provided with an ear extending through said closure plate, printing ribbons carried within said body, means for feeding said printing ribbons, an operating lever cooperating with said feeding means, means for pivotally securing said lever to said ear, a clutch throwing rod secured to one end of said operating lever, locking means carried by said casing and engaging one end of said clutch throwing rod for holding the rod against accidental longitudinal movement relative to said casing.

4. A device of the class described comprising a casing, a bottom plate secured to said casing and provided with an inwardly extending lug, ribbon feeding means carried within said body, a ribbon wound upon said ribbon feeding means, duplicating and recording sheets associated with said ribbon, means for printing therethrough, an operating lever coöperating with said ribbon

feeding means, an upwardly extending ear formed upon said base plate, said lever engaging said upwardly extending ear, a rod for detachably holding said lever in engagement with said ear, locking means carried by said casing, said rod engaging said locking means and normally held against longitudinal movement thereby, and means secured to said rod and extending through said casing for facilitating the removal of said lever from said ear and allowing longitudinal movement of said rod relative to said casing.

5. In a stamp, a relative movable casing and printing platen, the casing having a longitudinally slotted face plate, a rotatable disk in the casing having type bearing teeth, a longitudinally slidable bar supported between the face plate and type disk, having rack teeth on its under surface protectively intermeshing the type teeth of the disk, the upper face of said bar directly above the spaces between the rack teeth having a series of numbers corresponding to the character of the disks and being formed with a projection extending through said slot, said face plate being orificed to display a bar character in the disk position for stamping said display character.

6. In a stamp, a relatively movable casing and printing platen, the casing having a longitudinally slotted face plate, a rotatable disk in the casing having type bearing teeth, a longitudinally slidable bar supported between the face plate and type disk, having rack teeth on its under surface protectively intermeshing the type teeth of the disk, the upper face of said bar directly above the spaces between the rack teeth having a series of numbers corresponding to the character of the disks and being formed with a projection extending between said slot, said face plate being orificed to display a bar character in the disk position for stamping said display character, and a longitudinal spring-member supported under the face plate, having an end upwardly engaging between the rack teeth adapted to yield permitting the bar to be longitudinally adjusted.

7. A portable stamp comprising a housing body, having a slotted face plate, a platen plate on the other side of the body spaced for inserting the article to be stamped, said body and platen being relatively movable for impression, a toothed type disk in the body, one side of which is adjacent the platen and the other side adjacent the face plate, a bar longitudinally slidably supported between the face plate and type disk, indexed on its upper face relative to the characters of the type disk and having a projection through said face plate slot, its under surface being formed with rack teeth protectively intermeshing

- with the type teeth, and a spring member supported approximately in the plane of rack and disk engagement, having a knobbed free end engaging between the rack teeth 5 upon one side of the type teeth, yielding under a longitudinal movement of said rack bar and coacting therewith to move the same a definite step and to hold said rack and disk in said adjusted position for stamping.
- 10 8. A stamp comprising a relatively movable casing and platen plate, a rotatable disk in the casing having type-teeth, an interior supporting plate and exterior slotted face plate on one side of the disk, the diametrically opposite sides of the disk projecting through the casing adjacent the platen plate and through the supporting plate of the casing, the thickness of the casing being slightly greater than the diameter 15 of said disk, a bar longitudinally slid able on said supporting plate under the face plate, having a projection extending through said slot, the said bar having rack teeth on its under side protectively intermeshing the type-teeth, a spring member on said supporting plate having a free end projecting upwardly through said supporting plate into engagement between the rack bar teeth upon one side of the disk, the spaces between the rack teeth corresponding to the number of said type teeth, and the upper surface of the bar bearing a series 20 of characters directly above the spaces between the rack teeth serially corresponding to the characters of the disk, the face plate displaying a bar character corresponding to a disk character in stamping position.
- 25 9. A stamp comprising a casing having a supporting top and a bottom interior plate, a rotatable disk having type teeth peripherally projecting through the top and bottom plate, a platen adjacent the bottom plate, the casing and platen being relatively 30 movable, a slotted cover plate immediately adjacent the supporting top plate, a bar slid able between the top and cover plates, having a projection projecting through said slot, the bar having under rack teeth protectively intermeshing the type teeth, said bar being correspondingly indexed on its upper face, and a spring supported by the top plate extending upwardly and engaging between the teeth of the rack bar upon 35 one side of the type disk.
- 40 10. A stamp comprising a relatively movable casing and printing platen, normalizing means therefor, a rotatable disk in the casing having type teeth, inking and paper feeding devices within the casing disposed upon opposite sides of the disk, the thickness of the casing being approximately that of the type disk, a cover slotted plate for the casing, and a supporting plate immediately under the cover plate through which
- the upper periphery of the type disk projects, the platen being upon the under side of the casing, an index rack bar slideable between the supporting plate and cover plate protectively intermeshing the type teeth, a spring engaging upwardly between the spaces of the rack teeth, and means actuated by the relative movement of the platen and casing to operate said inking and paper feed during said normalizing movement.
- 45 11. A stamp comprising a relatively movable casing and printing platen, normalizing means therefor, a rotatable disk in the casing having type teeth, a type-teeth intermeshing indexed rack bar on one side of the casing between the disk and cover plate, the spaces between the type-teeth corresponding numerically to the type-teeth, the platen being on the other side, and the thickness of the casing being approximately that of the diameter of the printing disk.
- 50 12. A stamp comprising a relatively movable casing and printing platen, normalizing means spacing them for the insertion of the article to be stamped, a rotatable disk in the casing having type-teeth, disk operating, locking and indexing devices on one side of the casing, the platen being on the other side, the thickness of the casing being approximately equal to the diameter of the printing disk, and a cover plate for the casing through which the disk operating means are projected and the index displayed.
- 55 13. A stamp comprising a casing, a rotatable disk in the casing having type-teeth, a platen coacting with the disk upon one side of the casing, index rack bars co-operating with the disk diagrammatically upon the under side of the top member of the casing operable and displayed through the casing cover plate, said bars being movable in the tangential plane of the disk immediately under the cover plate.
- 60 14. A stamp comprising a casing, a rotatable disk in the casing having type-teeth, a platen coacting with the disk upon one side of the casing, index rack bars co-operating with the disk diametrically upon the under side of the top member of the casing operable and displayed through the casing cover plate, said bars being movable in the tangential plane of the disk immediately under the cover plate, and a spring member immediately under the rack bar upon one side of the disk and having a free end engaging upwardly between the spaces of the rack teeth.
- 65 15. A stamp comprising a relatively movable casing and platen plate, a rotatable disk in the casing having type-teeth coacting with the platen on one side of the casing, a slotted cover plate for the casing immediately over the other side of the type disk, a slide-bar under the cover plate hav-

ing serial characters displayed through the cover plate, and an operating knob projected through said slot, the under surface of said bar and character having rack teeth 5 protectively intermeshing the type-teeth whereby the character to be stamped is indicated by the rack character displayed through the cover plate.

16. A stamp comprising a relatively 10 movable housing body and a coacting plate, a rotatable disk in the housing having type teeth coacting with the platen, a supporting plate and slotted cover plate on the other side of the housing formed with a narrow 15 slide-way substantially in a tangential plane of said disk, the disk periphery projecting through the supporting plate, a longitudinal bar movable under spring tension in the slide-way, said bar being formed with rack 20 teeth on its under side protectively intermeshing the type-teeth, the bar having a projection upwardly through the slotted cover plate the upper surface of said bar above the rack having serial characters 25 corresponding to the disk characters displayed through the cover plate to indicate the disk character on the other side of the housing in stamping position.

17. A portable stamp comprising a unitary housing body having a slotted cover plate, a platen plate coacting with the other side of said body, means enabling said body and plate to be moved to make an impression and return to normal position, a rotatable disk in the body having type-teeth co-operating with the platen, inking and record strip rolls and feed mechanisms, step-operated by the impression return, said rolls being disposed on opposite sides of the type 40 disk, and the feeding mechanism disposed on the side of the housing, the record and inking strips passing between the platen and type disk, for simultaneously stamping an inserted article and printing the record strip against said platen, disk operating, and indexing means supported under the cover plate and operating in the tangential plane of the disk periphery diametrically opposite to the platen.

50 18. In a portable stamp, a unitary housing having a cover plate, constituting a housing body for holding the operative elements, a platen plate coacting with the other side of said housing body, a rotatable disk in the housing having type-teeth to contact the platen, a slidable longitudinal bar having rack teeth on its under side protectively intermeshing the type-teeth diametrically opposite the platen, the upper surface of the bar slidably contacting the under surface of the cover plate, said plate being formed with a slot in the path of bar movement, a bar operating projection extending through said slot, the spaces between the 55 rack teeth corresponding serially to the

type-teeth, the upper surface of the bar corresponding to the spaces between the rack teeth having serial characters corresponding to the type-teeth, said cover plate being formed with an opening displaying a bar 79 character corresponding to the disk character in stamping position, and tension means influencing the rack bar movement.

19. A stamp comprising a unitary housing body having a cover plate at one side 75 and a coacting platen plate on the other side of the housing body, a series of equal diameter rotatable printing disks in the body diametrically approximately the thickness of the housing body, each formed with type 80 bearing teeth, said type comprising statement identifying, date and money indicating characters, a series of bars between the cover plate and type disks having rack teeth protectively intermeshing the type-teeth, a 85 series of springs imparting step movements to said bars, the spaces between the rack teeth corresponding to the characters of the type-teeth, said cover plate being formed with a series of longitudinal slots in the 90 path of travel of said bars, a series of characters on the upper face of each bar corresponding with its respective disk characters in stamping position, said bars having projections through their respective slots, said 95 cover plate being also formed with a transverse opening over the intermeshing rack and disk teeth for displaying in alignment characters indicating the disk characters in stamping position on the under side of the 100 housing body.

20. A stamp comprising a unitary housing body, and a hinged coacting platen plate on one side thereof, said body comprising an inner casing and a cover, a disk rotatable 105 in the inner casing having type-teeth, the thickness of the body approximating the diameter of the disk, record strip and inking strip rolls rotatably supported within the inner casing upon opposite sides of the 110 printing disk, the strips passing between the disk periphery and the platen supporting the article to be stamped, said rolls having toothed wheels on their outer ends between the side walls of the cover and the inner casing, spring controlled pawl, ratchet and lever mechanism for step feeding said rolls, supported between said casing and cover 115 side walls, said lever mechanism being operated by the relative movements of the platen and housing body, the spring control influencing the normalizing of said housing body and platen for inserting the article to be stamped, and a type tooth intermeshing 120 spring-controlled index bar supported between the upper surface of the inner casing and the under surface of the cover plate, having a manipulating member projected through the cover plate, said cover plate being formed to display a bar character cor- 125 130

responding to the disk character in printing position on the other side of the housing body.

21. A stamp comprising a unitary housing body, and coacting platen, normalizing means therefor, said housing body comprising an inner frame, and cover, a rotatable type disk, and record and inking strip rolls rotatable in the frame, said strips passing between the disk and the platen supporting the inserted article to be stamped, toothed wheels, pawl, ratchet and lever mechanism for step feeding said rolls, operated by the relative movement of the housing body and platen, said feed mechanism being supported on the side of said inner frame within the cover, and inner frame operated exteriorly of the cover for step adjusting the printing disk to predetermined stamping position relative to the platen.

22. A stamp comprising a unitary housing body, and coacting platen, said housing body comprising an inner frame, and cover, a rotatable type disk, record and inking stripping rolls rotatable in the frame, said strips passing between the disk and platen supporting the inserted article to be stamped, toothed wheels, pawl, ratchet and spring controlled lever mechanism for step feeding said rolls, operated by the relative movement of the housing body, and platen, said feed mechanism being supported on the side of said inner frame within the cover, said spring control influencing the normalizing of the housing body and platen for inserting the article to be stamped, the step feed being actuated by the spring reaction after a stamping operation, and disk adjusting means between the cover and casing operated exteriorly.

23. In a stamp, a casing, a rotatable printing disk therein having type-teeth, a supporting plate through which said disk projects, a slotted cover plate over the supporting plate, providing a slide-way between said plates, a bar in said slide-way having rack teeth on its under surface protectively intermeshing the type-teeth, a bar projection extended through the slotted cover plate, and a longitudinal spring, one end of which is secured to the supporting plate, its free end projecting upwardly and having a cam end engaging between rack teeth co-acting therewith when the bar is manually shifted to impart a definite step movement to the bar and hold the disk in adjusted stamping position.

24. In a stamp, a body portion comprising a box-like structure, a type-toothed wheel therein, said body portion being slightly greater in cross section than the diameter of said wheel, a pair of record strip rolls and a pair of pigment strip rolls on opposite sides of said wheel in substan-

tial alinement, one periphery of said wheel and the tangential portions of said strips projecting through one side of the housing for stamping, and means for adjusting said wheel supported in the opposite side of said body, said means being operatively disposed in the tangential plane of said wheel, accessible through the upper face of said body portion.

25. A pocket stamp comprising a box-like casing, a printing wheel therein, one side of which is exposed through one side of the casing, wheel positioning means in the tangential plane of the wheel accessible through the opposite side of the casing, record rolls and ir⁷⁵ mechanism in the casing disposing the record strip tangential to the printing side of the wheel, feed mechanism therefor in the casing, a platen coöperating with said casing, and means whereby a relative movement of casing and platen actuates said feed mechanism.

26. A stamp comprising a casing, a series of type toothed disks rotatable therein, the cross-sectional area of the casing being approximately equal to the diameter and width of the printing disks, a slotted cover plate for the upper side of the casing, a series of thin longitudinally movable bars between the upper disk peripheries and the cover plate having projections through said slots, rack teeth on the under side of the bars engaging the disk teeth, the upper faces of said bars displaying the disk characters through the cover appropriate to an adjusted stamping position, means imparting a step movement to said bars, record and inking strip rolls on opposite sides of the type disks, the strips passing tangentially over the under side of the disk peripheries, feed mechanism for said rolls, and a member movably supported relative to the under side of the casing normally holding the printing disks out of stamping position, and having connections with said feed mechanism for actuating them through said relative movement.

27. A stamp comprising a casing, a series of type toothed disks rotatable therein, the cross-sectional area of the casing being approximately equal to the diameter and width of the printing disks, a slotted cover plate for the upper side of the casing, a series of thin longitudinally movable bars between the upper disk peripheries and the cover plate having projections through said slots, rack teeth on the under side of the bars engaging the disk teeth, the upper faces of said bars displaying the disk characters through the cover appropriate to an adjusted stamping position, means imparting a step movement to said bars, record and inking strip rolls on opposite sides of the type disks, the strips passing tangentially over the under side of the disk peripheries, 130

feed mechanism for said rolls, said feed mechanisms being disposed between the side walls of the casing and cover, the longitudinal area of the casing being approximately equal to the width of the printing disks and the longitudinal dimensions of the feed mechanisms, and a member movably supported relative to the under side of the casing normally holding the printing disks out of stamping position, and having connections with said feed mechanism for actuating them through said relative movement.

28. A pocket stamp comprising a box-like casing body, a printing wheel therein, the wheel diameter and body cross section being of approximately equal dimensions, the upper portion of the wheel being operatively accessible through the upper face of the casing body, the diametrically opposite side of the wheel being exposed for impression on the under side of the casing body, a relatively movable platen plate coextensive with and on the under side of the casing body, and normalizing means enabling a stamping and return movement of the body and platen plate.

29. A pocket stamp comprising a box-like casing body, a printing wheel therein, the wheel diameter and body cross section being of approximately equal dimensions, the upper portion of the wheel being operatively accessible through the upper face of the casing body, wheel positioning, locking and indexing mechanism operatively disposed between the wheel and upper side of the casing and wheel, extending and operating in the tangential plane of the wheel, the diametrically opposite side of the wheel being exposed for impression on the under side of the casing body, a relatively movable platen plate coextensive with and on the under side of the casing body, and normalizing means enabling a stamping and return movement of the body and platen plate.

In testimony whereof I hereunto affix my signature in presence of two witnesses.

MEREDITH G. STANDLEY.
